CLAIM

The ornamental design for a spray paint gun light, as shown and described.

DESCRIPTION

FIG. 1 is a perspective view of a spray paint gun light showing my new design.

FIG. 2 is a front view of the spray paint gun light showing my new design.

FIG. 3 is a rear view of the spray paint gun light showing my new design.

FIG. 4 is a right-side view of the spray paint gun light showing my new design.

FIG. 5 is a left-side view of the spray paint gun light showing my new design.

FIG. 6 is a top view of the spray paint gun light showing my new design.

FIG. 7 is a bottom view of the spray paint gun light showing my new design; and,

FIG. 8 is a perspective view of the spray paint gun light showing my new design shown as being mounted to an exemplary spray paint gun.

In FIG. 3, the broken lines show portions of a spray paint gun light that form no part of the claimed design; In FIG. 8, the broken lines depict a spray paint gun that forms no part thereof.

1 Claim, 7 Drawing Sheets
